UNITED STATES PATENT OFFICE

LOUIS LEVI, OF WINTHROP, MASSACHUSETTS

WINDOW SCREEN

Application filed January 27, 1932. Serial No. 589,077.

This invention is an improvement on that disclosed by Letters Patent of the United States No. 1,783,732, granted to me December 2, 1930, said invention being embodied 5 in a window screen including a single inner frame carrying the usual screen fabric and invariable in size, a housing frame embracing the inner frame and formed to engage vertical screen guides on a window casing, the housing frame being variable in size horizontally and invariable vertically, and springs cooperating with said frames to permit convenient engagement of the housing frame with the screen guides, and compensate for variations in the distance 15 between the screen guides, caused by swelling and shrinking of the casing.

One object of the present invention is to provide improved means for slidably engaging the housing frame with the screen guides, whereby friction resistance to the movement of said frame on the guides is decreased, and the cost of construction is reduced.

Another object is to provide means for securing the springs to the housing frame during the operation of assembling the parts of said frame without the employment of special spring securing means, such as spot 25 welding or rivets, and thereby reducing the cost of manufacture.

Another object is to enable the screen fabric to be quickly applied to the inner frame by an unskilled person, and confined on said 35 frame by parts of the housing frame when the two frames are assembled, and quickly removed from the inner frame when the latter is removed from the housing frame, preparatory to the application of new fabric.

Of the accompanying drawing forming a part of this specification,—

Figure 1 is a side view showing a window screen embodying the present improvements, engaged with vertical screen guides.

Figure 2 is a side view showing the inner frame and the fabric filling, portions being broken away.

Figure 3 is a fragmentary view showing in section parts of the housing frame, and one 50 of the springs as secured by assembling said

parts, parts of the inner frame and screen fabric being shown in elevation.

Figure 4 is a section on line 4—4 of Figure 3.

Figure 5 is a section on line 5—5 of 55 Figure 1.

Figure 6 is a section on line 6—6 of Figure 1.

Figure 7 is a section on line 7—7 of Figure 1.

Figure 8 is a fragmentary side view showing a portion of the inner frame and a portion of a sheet of screen fabric as first applied to the frame.

Figure 9 is a section on line 9—9 of 65 Figure 8.

Figure 10 is a view similar to Figure 8 showing the fabric sheet folded to provide the flanges hereinafter described.

Figure 11 is a section on line 11 of 70 Figure 10.

Figure 12 shows the housing frame alone in perspective and considerably out of proportion.

The same reference characters indicate the 75 same parts in all of the figures.

In the drawing 15 designates the invariable inner frame, and 16 the sheet of screen fabric constituting the filling of said frame. The horizontally variable sheet metal housing 80 frame surrounding the inner frame is composed as heretofore of two angular end sections, one of which is designated as a whole by 17, and the other by 18 in Figure 12. Each section includes, as heretofore, a vertical member constituting one end of the frame, and two horizontal members fixed by electric welding, or otherwise, to end portions of the vertical members and telescopically interengaged as heretofore with complementary horizontal members fixed to the vertical member of the other section. Each of the members of each section includes a neck and two substantially parallel flanges 85 connected with the neck.

The necks of the vertical members are designated by 19, and the flanges by 20. The necks of the horizontal members are designated by 19^a, and the flanges by 20^a.

I have improved the vertical and horizontal 100

members of the housing frame, as next described, to adapt said frame to run with a minimum of frictional resistance on the usual vertical screen guides *a a* (Figures 1 and 7).

The necks 19 of the vertical members instead of having guide-engaging grooves extending from end to end as disclosed by my former patent, have substantially flat or slightly convex outer sides constituting elongated runners bearing only on the outer edges 10 of the screen guides, without bearing on the opposite sides thereof, as shown by Figure 7.

The end portions of the vertical members are inserted between the flanges 20^a of the horizontal members and united thereto preferably by spot welding indicated by 21, (Figure 12).

The flanges 20^a of the horizontal members are extended outward from the ends of the necks 19^a to form short parallel ears 22 constituting lateral runners bearing on opposite sides of the guides and preventing sidewise displacement of the housing frame relative to the guides. It will be seen that the described elongated runners, or necks, and short lateral runners, or ears, not only enable the housing frame to slide freely on the screen guides, but also prevent the passage of insects through the screen. Moreover, the cost of manufacture is materially reduced by eliminating the operation of forming the guide-engaging grooves in the necks of the vertical members of the housing frame, required by the construction disclosed by my former patent.

The springs interposed between the vertical members of the housing frame and the vertical members of the inner frame to automatically elongate, and permit the contraction of the housing frame, horizontally, and 40 maintain the runner portions of the housing frame in yielding engagement with the screen guides, as disclosed by my former patent, are, in accordance with the present invention, bowed springs 23 which bear at their ends on the necks 19 of the vertical members of the housing frame, and exert pressure at their midlength portions on vertical members of the inner frame 15.

Each spring has a hook 24 at one end engaged with an end of a vertical neck 19, and confined in such engagement by an end portion of a horizontal neck 19^a as shown by Figure 3.

The several hooks 24 are engaged with the vertical necks 19 before the members of the housing frame are assembled, so that the assembling operation causes the horizontal necks 19^a to bear on the hooks and prevent their displacement from the position shown by Figure 3.

The opposite end of the spring is adapted to slide on the vertical neck 19 with which the hook is engaged. The end portions of the vertical necks 19 are preferably indented to 65 receive the outer portions of the hooks 24, so

that said portions are flush with the outer sides of the necks, as shown by Figure 3.

The springs are quickly secured by the described means, and the use of special securing means, such as rivets or spot welding, and the expense involved thereby, is eliminated. The mid length portions of the springs 23 are concavo-convex in cross section so that their outer sides are recessed to maintain the springs in engagement with the inner frame 75 as indicated by Figure 4.

My improvements include the connection hereinafter described between the screen fabric 16 and the inner frame 15, whereby a person without skill in screen making may quickly apply a sheet of screen fabric to, and remove it from the screen and cause its secure retention in its operative position by inserting the inner frame in the housing frame. The sheet 16 of screen fabric employed is of greater area than the inner frame 15 so that when placed on one side of said frame as indicated by Figures 8 and 9 it has free marginal portions 16^a projecting from the frame. Said marginal portions are then folded to form fabric flanges 16^b extending across the margin and upon the opposite side of the frame, as shown by Figures 10 and 11. When the inner frame 15 is inserted in the housing frame, as shown by Figures 3, 5 and 6, the fabric flanges are confined on the inner frame by the flanges of the housing frame members.

The fabric is readily separable from the inner frame by unfolding the flanges thereof when the frame is withdrawn from the housing frame, and is quickly replaceable by another sheet.

The corners of the fabric sheet may be cut off to form diagonal edges 16^c to provide the fabric flanges with oblique ends extending side by side on the inner frame without overlapping.

I claim:

1. A window screen of the character stated comprising an invariable inner frame having a filling of screen fabric, and a horizontally variable sheet metal housing frame surrounding the inner frame and composed of two angular end sections telescopically interengaged to vary the length of the housing frame, said sections including vertical and horizontal members, each having a neck and substantially parallel flanges connected thereby, end portions of the flanges of the vertical members being inserted between and fixed to end portions of the flanges of the horizontal members, the necks of the vertical members constituting elongated runners adapted to contact with and slide freely on the inner edges of vertical screen guides, and the flanges of the horizontal members being extended from the necks thereof to form short spaced apart ears constituting lateral runners adapted to contact with and slide freely on opposite sides of said guides,

so that the areas of contact between the housing frame and the screen guides are reduced to a minimum, with a corresponding reduction of friction.

- 5 2. A window screen of the character stated comprising an inner frame, a filling of screen fabric thereon, a horizontally variable sheet metal housing frame surrounding the inner frame, opposite vertical members
10 of the housing frame being engaged with and slidable on screen guides, and springs interposed between the guide engaging members of the outer frame and corresponding members of the inner frame, to compensate
15 for variations of the distance between the screen guides, said springs having end portions bearing on the said guide-engaging members, and bowed mid length portions exerting pressure on the inner frame, said
20 mid length portions being recessed to maintain the springs in engagement with the inner frame.

3. A window screen as specified by claim 1, comprising also bowed springs bearing
25 at their ends on the necks of the vertical members of the housing frame and exerting pressure at their mid length portions on vertical members of the inner frame, each spring having a hook at one end engaged with an
30 end portion of the neck of a vertical member of the housing frame, and confined in such engagement by an end portion of the neck of a horizontal member.

4. A window screen of the character stated
25 comprising an inner frame, a filling of screen fabric thereon, and a horizontally variable sheet metal housing frame surrounding the inner frame, and having spaced apart flanges, opposite ends of the housing frame
40 being formed to engage and slide on screen guides, the inner frame being inserted between flanges of the housing frame, the screen fabric being a sheet of greater area than the inner frame, so that the sheet, when
45 placed on one side of the inner frame, has free marginal portions which are folded to form fabric flanges extending across the margin and upon the opposite side of the frame, said fabric flanges being confined on the
50 inner frame by flanges of the housing frame when the two frames are assembled, the fabric being separable from the inner frame by unfolding the fabric flanges when the two frames are separated.
- 55 5. A window screen as specified by claim 4, the screen fabric sheet being cut away at its corners to provide the fabric flanges with oblique ends extending side by side on the inner frame, without overlapping.
- 60 In testimony whereof I have affixed my signature.

LOUIS LEVI.
